UNITED STATES PATENT OFFICE.

FERNAND MAURICE CHARLES, OF IVER HEATH, ENGLAND.

CONSTRUCTION OF BODIES OF MOTOR AND OTHER VEHICLES.

1,342,664.

Specification of Letters Patent.

Patented June 8, 1920.

Application filed February 26, 1919. Serial No. 279,390.

To all whom it may concern:

Be it known that I, FERNAND MAURICE CHARLES, a subject of the King of Great Britain and Ireland, and residing at Brackenwood, Iver Heath, Buckinghamshire, England, have invented certain new and useful Improvements in the Construction of Bodies of Motor and other Vehicles, of which the following is a specification.

10 This invention relates to the construction of bodies of motor and other vehicles, either complete or in sectional parts.

Hitherto when these have been made of sheet metal their manufacture has involved considerable labor and especially so when the bodies are of a curved profile or form. In comparison with the latter, rectangular or straight shapes involve the cutting out of the sheet metal, bending thereof in one plane only so that but little skill is required; but in a body possessing curved outlines considerable labor is involved in covering the internal structure with a sheet of metal properly hammered to shape, the latter operation involving a very slow process which is carried out successfully only through the employment of very highly skilled labor.

The object of the present invention is to overcome the difficulties which have been hitherto experienced in the manufacture of such articles, to lessen the labor involved, to increase the speed of production and the exact and standardized reproduction of the body, as well as the spare and other parts thereof.

The invention will now be described with reference to the accompanying drawings in which:

Figure 1 is a perspective view of one form 40 of motor body which may be constructed according to the present invention.

Fig. 2 is a diagrammatic view in side elevation of an electrolytic plant that may preferably be used in connection with the 45 present invention.

Fig. 3 is a transverse section on the line 3—3 of Fig. 2.

Fig. 4 is a cross section of a mold or pattern for forming a door of the body and 50 also shows the deposited layer as just removed.

Fig. 5 is a perspective view of the mold in Fig. 4.

Fig. 6 is a perspective view of the deposited layer.

Fig. 7 is a perspective view of one of the

sectional parts with a reinforcement applied thereto.

Fig. 8 is a cross section of Fig. 7.

Fig. 9 is a longitudinal section of the 60 vat and,

Fig. 10 is a transverse section thereof.

In carrying the invention into effect, the motor body *a*, Fig. 1, may be constructed as a single unit or may be built up from 65 a number of separate sectional units each formed wholly or partly by electrodeposition. Thus the body may be composed of a rear section *b*, intermediate section *c*, front or dashboard section *d* and doors *e*, and in 70 the following description there is described the manufacture of a door panel by way of example.

Referring more particularly to Figs. 4 and 5, the pattern or mold *f* corresponding 75 in shape and curvature with a door, is recessed or grooved at *g* and *g'* to receive suitable frame bars *h* and *k* which are made up in advance. These bars in the example shown are of respectively T and angle sec- 80 tion as indicated in Fig. 4 and when in position on the pattern they lie flush with the exterior. The pattern is made of wood, metal, or any other suitable material and after having been rendered a conductor of 85 electricity, it is ready to undergo electrolysis. If further strength is necessary provision may be made for transverse frame bars, and such pattern may, if desired, be made in sections capable of being taken 90 apart.

The mold thus prepared constitutes a cathode member *l* and as shown in Figs. 3 and 10 is combined with an anode member *m* in such a way that together the two members 95 form a box-like container or bath which is fitted with the necessary current leads leading to a generator diagrammatically shown in Fig. 10, and the usual insulation is provided to prevent short circuiting. Preferably one long wall of the bath is formed wholly or partly of the material it is desired to use, for example copper, and forms the anode, spaced apart from which is the other wall or cathode, consisting of 100 105 the mold, these members being separated by insulation *n*.

Referring more particularly to Fig. 2, the electrolytic plant which it is preferred to employ in connection with the invention 110 may comprise an upper tank *o* supported by girder framing *p*, such tank containing

a suitable electrolyte such as a solution of sulfate of copper and dilute sulfuric acid, when copper is the metal to be deposited. The bottom of the tank *o* has an outlet *q* controlled by a valve *r* which is manually operable by a rod *s*, lever *t*, fulcrumed at *u*, and a chain or rod *v* within reach of the operator on the ground. If desired, the liquor in the tank may be under pressure, 10 pressed air for example, and when the valve *r* is opened, the liquor passes into a rose or distributing head *w* from which depends one or a series of flexible pipes *x* of rubber or other suitable material. The two part 15 container or vat is arranged in position on the floor *y* beneath the tank *o* and the ends of the flexible pipes are led through a suitable cover or otherwise so that the electrolyte may be fed into the space between the 20 anode and the cathode, while the bottom of the vat has escape ducts discharging into a sump or lower tank *z* arranged in the foundation 2. A return pipe *3* is provided which extends from the tank *z* up to the tank *o* 25 whereby the liquor may be passed up into the latter by means of the pump *4* which is indicated as being driven by an electric motor *5* which may also drive a dynamo to supply the necessary current for the electrolytic vat. The lower end of the return pipe *3* is fitted with a filter or screen, and access 30 to the upper tank is afforded by the ladder shown.

As shown in Figs. 9 and 10, the vat is 35 constituted by side members *l* and *m*, separated by end insulating members *n* which may be made of cellulose fiber or other suitable material. The four-sided container is closed in by top and bottom plates *9* and 40 *10*. The parts are detachably clamped together by means of hinged clamps *11*, as shown.

By arranging the electrolytic vat in the manner shown, a vigorous circulation of the 45 electrolyte is maintained over all the surfaces to be plated, by means of the pump shown, or the pressure in the upper tank, or both combined, so as to insure a considerable degree of friction on the depositing 50 surface and to maintain a rich supply of the desired metal at the cathode while any local impoverishing of the active liquor is prevented. The flow velocity is variable by controlling the action of the pump accordingly.

When a sufficiency of metal has been deposited, the electric leads to the vat are disconnected, the valve *r* is closed and the vat is allowed to empty into the lower tank. 60 The vat is then removed and then opened or taken apart and the thin deposited metal sheet *6* with its adhering frame bars removed from the pattern. The door panel thus formed may then if desired be 65 strengthened or reinforced and this is ef-

fected preferably as shown in Figs. 7 and 8, according to which the space between the frame bars *h*, *k*, is filled in with wire mesh 7 expanded metal, or so forth, after which a layer 8 of pulp is applied to the mesh which is pressed through the interstices so that a firm solid backing is obtained to the sheet 6. The reinforcing medium may suitably consist of sulfite cellulose, cellulose acetate product, papier mâché, wood pulp or other suitable or similar plastic and moldable material.

From the foregoing it will be understood that any of the sections *b* to *e* of a car body may be manufactured by electrolysis or two 80 or more may be made simultaneously. If desired and instead of the method above described, the framing may first be built up and the wire mesh and pulp reinforcement applied, after which the structure is bodily 85 immersed in a vat through which the liquor is adapted to circulate at high speed.

Besides the production of bodies, mudguards, motor engine bonnets, dashboards and similar accessories may be manufactured 90 by the described system of electrodeposition. Moreover, the detailed construction of the bath and the flow velocity of the liquor will naturally depend upon the nature and shape of the article it is desired to produce without interfering with the principle of a rapidly moving electrolytic body of liquid. 95

Having now described my invention, what I claim as new and desire to secure by Letters Patent is:—

1. A process of manufacturing motor bodies and accessory parts therefor, which consists in forming a pattern of the desired profile, grooving or recessing said pattern to receive framing bars, placing framing bars within the grooves formed in the pattern, rendering the surface of the pattern thus formed electroconductive, subjecting said pattern to the action of an electrolyte in a vat, passing an electric current through said vat thereby depositing a layer of metal upon the pattern, and removing the said layer with the framing bars attached thereto.

2. A process of manufacturing motor bodies and accessory parts therefor, which consists in forming a non-conductive pattern of the desired profile, grooving or recessing said pattern to receive framing bars, placing framing bars within the grooves formed in the pattern, rendering the surface of the pattern thus formed electroconductive, subjecting said pattern to the action of an electrolyte in the vat, passing an electric current through said vat, thereby depositing a layer of metal upon the pattern, removing said layer with the framing bars attached thereto, and reinforcing the said deposited metal layer.

3. A process of manufacturing motor bodies and accessory parts therefor, which

- consists in forming a pattern of the desired profile, grooving or recessing said pattern to receive framing bars, placing framing bars within the grooves formed in the pattern, 5 rendering the surface of the pattern thus formed electroconductive, subjecting said pattern to the action of an electrolyte in the vat, passing an electric current through said vat thereby depositing a layer of metal upon 10 the pattern, maintaining a rapid circulation of electrolyte through the said bath whereby a layer of metal will be deposited upon the pattern, and removing said layer with the framing bars attached thereto.
- 15 4. A new article of manufacture, comprising an electrolytically deposited motor body
- part as a single layer or sheet, and framing bars attached to the said layer.
5. A new article of manufacture, comprising an electrolytically deposited motor body 20 part as a single layer or sheet, framing bars attached to the said layer and reinforcement for said motor body part.
6. A new article of manufacture, comprising an electrolytically deposited motor body 25 part, framing bars attached thereto, wire meshing interposed between the said framing bars and a plastic moldable mass adhering to the said mesh.

In testimony whereof I have signed my 30 name to this specification.

FERNAND MAURICE CHARLES.
